DESIGN FOR A CRUCIFIX

Henry A. Schwennesen, Chicago, Ill., assignor to
Max B. Waterman, Chicago, Ill.

Application July 27, 1935, Serial No. 57,830

Term of patent 3½ years

To all whom it may concern:

Be it known that I, Henry A. Schwennesen, a citizen of the United States, residing at 1702 N. Kedvale Avenue, city of Chicago, county of Cook, and State of Illinois, have invented a new, original, and ornamental Design for Crucifixes, of which the following is a specification, reference being had to the accompanying drawing, forming part thereof.

Figure 1 is a plan view of a crucifix showing by new design.

Figure 2 is a sectional view taken along lines of 2—2 of Figure 1.

I claim:

The ornamental design for a crucifix as shown.

HENRY A. SCHWENNESEN.
